UNITED STATES PATENT OFFICE.

GEORGE H. WHITTINGHAM, OF BALTIMORE, MARYLAND, ASSIGNOR TO MONITOR CONTROLLER COMPANY OF BALTIMORE, A CORPORATION OF MARYLAND.

ELECTRIC SWITCH.

1,362,379.

Specification of Letters Patent. Patented Dec. 14, 1920.

Application filed February 28, 1920. Serial No. 362,046.

To all whom it may concern:

Be it known that I, GEORGE H. WHITTINGHAM, a citizen of the United States, residing at Baltimore, in the State of Maryland, 5 have invented certain new and useful Improvements in Electric Switches, of which the following is a specification.

The purpose of this invention is to provide a yieldingly mounted contact finger 10 for an electric switch, which finger with its support can be cheaply manufactured and readily assembled and taken apart, and which possesses other advantages herein-after pointed out.

15 In the accompanying drawing,

Figure 1 is a side elevation of a switch embodying my improvements;

Fig. 2 is a top plan view of the same, the movable member of the switch being 20 omitted;

Fig. 3 is a perspective view of the contact finger;

Fig. 4 is a similar view of the base or supporting member for the contact finger;

25 Fig. 5 is a perspective view of a base or support showing a modified form of hook; and,

Fig. 6 is a central longitudinal section 30 through a contact finger connected to a base like that shown in Fig. 5.

Referring to Figs. 1 to 4, inclusive, of the drawing, A indicates a base or supporting member; B indicates a contact finger carried by said member, and C indicates, 35 conventionally, a movable contact member which co-operates with the contact finger to form a switch. In this illustration the movable member is indicated as part of a drum controller. The supporting member, 40 as shown, consists of a flat strip of metal 1, having at one end a transverse slot 1^a and having its opposite end 1^b turned outwardly at right angles to the body, to form a stop for the finger. In the central part of the 45 strip 1 is arranged a hook 2, which projects at the same side of the body as the stop portion 1^b. This hook member or catch may be formed in various ways. As shown in Figs. 1 and 4, it consists of a short piece 50 of flat metal bar, riveted or otherwise secured to the piece 1 and arranged edgewise with respect to the ends of said base. A deep notch 2^a extends inwardly from the rear edge of the part 2, and the part 2^b,

overhanging this notch, serves as a catch 55 for retaining one end of the spring on the finger, as hereinafter explained.

The body 3 of the finger is composed of a flat metal strip, preferably having its edges 3^a turned over, to strengthen the 60 finger, and having one end portion 3^b bent downwardly, forming a tongue adapted to fit into the slot 1^a in the base. The downwardly bent portion has shoulders 3^c which rest upon the base when the end portion 65 3^b is within the slot 1^a. The finger has in its central portion a longitudinal slot 3^d, adapted to receive the hook 2 on the base, the slot however being considerably longer 70 than the width of the hook. The forward 75 end of the finger is provided with a contact piece 4, suitably secured thereto, as by means of a rivet 5. Upon the upper side of the finger is secured a bow spring 6, formed from a flat metal strip, the bend 75 6^a in the spring being at the rear end of the finger and the free end 6^b of the spring extending over the slot 3^d. This spring is secured to the finger by a rivet 7 which passes through the spring and through a 80 flexible connector 8, composed of a plurality of thin copper strips, the end of this connector being arranged between the spring and the finger.

In assembling the support and finger, the 85 hook 2 is passed through the slot 3^d from the underside of the finger and moved to the forward end of the slot. The free end of the spring is then pressed downwardly 90 into line with the notch in the hook and the base and hook are moved rearwardly relatively to the finger until the tongue 3^b drops into the slot 1^a in the base. The spring will then exert an upward pressure 95 on the hook and the finger will be supported at its rear end by the shoulders 3^c and near its forward end by the stop 1^b. To remove the finger from the base, the tongue 3^b is pulled out of the slot 1^a, and by moving the finger rearwardly the spring 100 will be drawn out of engagement with the hook and the base can then be removed by withdrawing the hook from engagement with the slot 3^b.

It will be noted that the spring at its 105 free end is wider than the slot 3^d, and when the finger is rocked upwardly, as shown in dotted lines in Fig. 1, the spring, resting

upon the finger, will form a stop to prevent further movement of the finger. It is to be noted that the flexible connector 8 is secured between the spring and the top of the finger and that at the point where this connector leaves the finger, the spring and the end of the finger are curved in opposite directions. If the connector is moved upwardly or downwardly relatively to the finger, it will bend around these curved surfaces and will not be injured, as might be the case if the surfaces were angular.

Fig. 5 shows a form of base or support for a contact finger with a modified form 15 of hook; and Fig. 6 shows a contact finger applied to this base. In Fig. 5 the base 9 is the same as in the previously described figures except that a slot 10 is cut through the stop portion 9^b at the point where said portion joins the body of the base, and the hook 11 in this instance is formed by bending a flat strip of metal oppositely at two points, to provide a foot piece 11^a, which rests upon the base and extends into the slot 10, an upright portion 11^b, and hook portion 11^c, the latter for engaging the spring on the finger. A single rivet 12 secures the hook to the base and the hook is prevented from turning on the base by the engagement of the part 11^a with the slot 10. With this form of hook, the slot 13 in the finger, must of course be made wider than the corresponding slot 3^a in Fig. 3; but otherwise no change is required in the finger. The parts are assembled and taken apart in the same manner as described in connection with the preceding figures, and the functions are alike. The hook 11 affords a broader bearing surface on the end 40 of the spring than does the hook 2 of Figs. 1 to 4.

What I claim is:

1. In an electric switch, a supporting bar having a slot at one end and a hook member projecting from its central portion, a contact finger having one end engaging said slot, and a spring actuated member connected to said finger and detachably engaging said hook member.
2. In an electric switch, a supporting bar having a slot at one end and a hook-member projecting from its central portion, a contact finger having one end engaging said slot, and a bow spring secured to said fin-

ger and detachably engaging said hook-member.

3. In an electric switch, a supporting bar having a slot at one end, a contact finger having a tongue adapted to engage said slot, 55 said contact finger having a longitudinal slot in its central portion, a hook on said bar adapted to extend through said longitudinal slot, and a spring secured to said finger and engaging said hook.

4. In an electric switch, a supporting bar having a slot at one end, a contact finger having a tongue adapted to engage said slot, 65 said contact finger having a longitudinal slot in its central portion, a hook on said bar adapted to extend through said longitudinal slot, and a spring of flat metal, of greater width than said longitudinal slot, secured to said finger and engaging said hook.

5. In an electric switch, a supporting bar having a slot at one end, a contact finger having a tongue adapted to engage said slot, 75 said contact finger having a longitudinal slot in its central portion, a hook on said bar adapted to extend through said longitudinal slot, and a bow spring secured at one end to said finger and extending rearwardly thereon and thence forwardly and engaging said hook.

6. In an electric switch, a supporting bar having a hook thereon, a contact finger having its rear end curved downwardly and adapted to rest on said bar, a bow spring having one end secured to said bar and extending rearwardly thereon and thence bent upwardly and forwardly and engaging said hook, and a flexible connector secured between said spring and bar.

7. In an electric switch, a supporting 90 member comprising a flat bar having one end offset to form a stop and having a transverse slot at its opposite end and a hook member projecting from the central portion of the bar, in combination with a 95 contact finger having a tongue at one end adapted to engage said transverse slot, and having a longitudinal slot in its central portion adapted to receive said hook member, and a spring on said finger adapted to engage said hook.

In testimony whereof I affix my signature.

— GEORGE H. WHITTINGHAM.
